UNITED STATES PATENT OFFICE.

JOHN McKLUSKY, OF NEW HAVEN, CONNECTICUT.

INTERNAL-COMBUSTION ENGINE.

Application filed August 11, 1927. Serial No. 212,218.

This invention relates to an improvement in internal combustion engines and particularly to that class of internal combustion engines having a rotary group of radially-arranged cylinders.

The object of this invention is to produce a simple, efficient and reliable engine of the class described, constructed with particular reference to fewness of parts.

With this object in view, my invention consists in an internal combustion engine characterized by having a stationary casing formed with one or more ports and a rotary group of radially-arranged cylinders located in the casing and each of which is also provided with a port adapted to successively register with the one or more ports of the casing, whereby valves may be dispensed with, together with the cams, levers, etc., for operating the same.

My invention further consists in an internal combustion engine characterized as above and having the stationary casing provided with a scavenging-air port, so that air, under pressure, may be passed through the cylinders to rid them of residual burned gases.

My invention further consists in an internal combustion engine having certain details of construction and combination of parts as will be hereinafter described and particularly recited in the claims.

In the accompanying drawings:

Fig. 1 is a view in rear elevation of an internal combustion engine constructed in accordance with my invention;

Fig. 2 is a side view thereof;

Fig. 3 is a view in rear elevation on a slightly enlarged scale with the two halves of the rear casing-plate removed;

Fig. 4 is a vertical central sectional view on an enlarged scale taken on the line 4—4 of Fig. 1;

Figs. 5^a and 5^b are complementary views in central transverse section on the line 5—5 of Fig. 2 on the same scale as Fig. 4;

Fig. 6 is a broken detailed sectional view on a greatly enlarged scale taken on the line 6—6 of Fig. 1;

Fig. 7 is a broken sectional view on the line 7—7 of Fig. 6;

Fig. 8 is a detached perspective view of one of the expandible packing-rings;

Fig. 9 is a corresponding view of one of the segmental guard-plates; and

Fig. 10 is a similar view of one of the corrugated guard-plate springs.

The internal combustion engine herein chosen for illustration is particularly designed for use in aircraft and consists of a radially-arranged group of six cylinders 10 bolted at their outer ends to a coupling-ring 11 which serves to tie the said cylinders together and is provided upon its periphery with a relatively-thin hardened-steel facing ring 12. At their inner ends each of the said cylinders 10 is clamped between the front and rear halves 13 and 13^a respectively of a crank-case ring 14, the front and rear faces of which are respectively provided with disk-like end-plates 15 and 16.

Each cylinder is provided with a steel lining-tube 17 which abuts at its outer end against the inner periphery of the coupling-ring 11 aforesaid in line with a circular passage or port 18 extending radially therethrough and through the facing-ring 12 aforesaid.

Each of the end-plates 15 and 16 of the crank-case before referred to is provided with an outwardly-projecting hub 19, between the interior of which and the opposite ends 20 and 21 of a two-part stationary hollow crank-shaft 22 are interposed anti-friction bearings 23, so that the end-plates 15 and 16, crank-case ring 13, cylinders 10, rings 11 and 12, as a group, together with parts connected therewith, may revolve about the crank-shaft with a minimum of friction. The eccentric central portion 24 of the stationary hollow crank-shaft 22 is shouldered, as shown, to mount a pair of anti-friction bearings 25 which are interposed between it and the hub 26 of a master connecting-rod 27 which is connected to one of the pistons 28. Pivoted to the hub 26 of the master connecting-rod 27 by means of wrist-pins 29 are a series of five connecting-rods 30, each of which latter, like the master connecting-rod 27, is pivoted at its outer end to one of the pistons 28,—all in the manner common to internal combustion engines of this type.

In line with and arranged around the outside of the coupling-ring 11 and facing-ring 12, I locate a stationary cylinder-head ring 31, diametrically divided into semicircular upper and lower halves 32 and 33 respectively. The interior diameter of the said cylinder-head ring is slightly larger than the exterior diameter of the facing-ring 12, so that the

latter, together with the cylinders, may revolve within the said cylinder-head ring without actual contact.

The forward face of the cylinder-head ring 5 just referred to is provided with a two-part casing-plate 34, also diametrically divided to form an upper half 35 and a lower half 36, each of which is formed with ventilating-openings 37 and with half of an outwardly-projecting bearing-sleeve 38, between the interior of which and the hollow propeller-shaft 39 is interposed an anti-friction bearing 40, as shown. The propeller-shaft 39 just referred to is coupled to the hub 19 of the revolving crank-case end-plate 15 by means of bolts 41, as shown in Fig. 4.

The rear face of the cylinder-head ring 31, like its front face, is provided with a casing-plate 42 diametrically divided to form an upper half 43 and a lower half 44, each of which is formed with ventilating-openings 45 and is secured at its inner end to an inwardly-projecting hub-plate 46, which latter is coupled to the crank-shaft 22 by means of a key 47, so that the said crank-shaft is held stationary with the engine-casing which comprises the casing-plates 34 and 42 and the cylinder-head ring 31.

The lower half 33 of the cylinder-head ring 31 is formed with an exhaust-port 48, a scavenging-air port 49, and an inlet port 50, each of which passes radially through the said cylinder-head ring in line with the ports 18 in the rings 11 and 12, and hence in line with the open outer ends of the cylinder 10, as shown in Figs. 5^a and 5^b.

To provide for a passage of scavenging air through the cylinders 10, each is formed near its inner end with a series of radial ports 51 which also extend through the lining-tube 17 of the cylinder, as clearly shown in Figs. 4, 5^a and 5^b. These ports just referred to are so located in the cylinder 10 that they are uncovered by the pistons 28 when the same reach the limit of their inward radial travel. Around each of the pistons 10 and in line with the ports 51 thereof, I form in the two halves of the crank-case ring 14 a circumferential air-channel 52, each of which is in communication with a sloping radial air-pipe 53 which, in turn, opens at its inner end into an annular air-chamber 54 (Fig. 4), which latter is supplied with air under pressure through a passage 55 formed in the hub-plate 46 forming part of the rear casing-plate 42 aforesaid.

To prevent the exploding gases from escaping laterally across the upper face of the upper half 32 of the cylinder-head ring 31, which is the point at which it is intended to have the explosion-cycle of my improved engine take place, I locate on each of the opposite sides of the group of cylinders 10 a segmental guard-plate 57 which is positioned in a segmental groove 58 located in the said upper half 32

of the cylinder-head ring 31. A corrugated spring 59, located in the groove 58 above the guard-plate 57, tends to maintain the latter in yielding contact with the periphery of the facing-ring 12.

Between each of the segmental grooves 58 above referred to and the side of the cylinder-head ring 31 adjacent thereto respectively, I form in the latter an internal annular groove 60 which receives a split resilient packing-ring 61 which is proportioned to normally hug the periphery of the facing-ring 12. One end of each of the said rings 61 abuts against a stop-pin 62 (Fig. 7), while its opposite end is formed with an outwardly-offsetting ear 63 which is engaged by a cam 64 for expanding the said ring to free it from contact with the facing-ring 12, as will be hereinafter described. The two cams 64, which respectively coact with the ears 63 of the respective packing-rings 61, are both mounted upon a common shaft 65 extending transversely through the upper half 32 of the cylinder-head ring 31, as clearly shown in Fig. 6. One end of the said shaft 65 is provided with an operating-handle 66 by means of which it may be turned to expand the ring 61, while its opposite end is provided with a retaining-nut 67.

It is intended that the packing-rings 61 shall only remain in contact with the facing-ring 12 for a short interval immediately following the starting of my improved engine, and only until the same attains a normal operating speed. When a proper speed has been attained, the handle 66 is operated to turn the cams 64 with the effect of expanding both of the packing-rings 61 into the position indicated by broken lines in Fig. 7, so that the rotating parts of my improved engine, including the cylinders 10, coupling-ring 11 and facing-ring 12, are freed of any frictional restraint by the said packing-ring 61, and destructive friction between the said packing-rings and the facing-ring 12 is avoided.

To prevent the escape of gases when the packing-rings 61 have been expanded out of engagement with the facing-ring 12, as above described, I secure by means of screws 68 to each of the opposite sides of the coupling-ring 11 a washer-like mercury packing-ring 69, the opposite face of each of which, near the periphery thereof, is formed with an annular series of impeller-notches 70 which extend into annular internal mercury chambers 71, one of which is located near the front and rear faces, respectively, of the engine. The front mercury chamber 71 is formed partly in the front end of the cylinder-head ring 31 and partly in the inner face of the front casing-plate 34, while the corresponding rear mercury-chamber 71 is formed partly in the rear face of the said cylinder-head ring and partly in the inner face of the rear casing-plate 42, as clearly shown in Fig. 4. When

the engine has attained sufficient speed and after the packing-rings 61 have been expanded to free them of contact with the facing-ring 12, the impeller-notches of the mercury 5 packing-ring 69 will act to throw mercury, which is stored in the chambers 71, outward with sufficient force to effectually prevent the lateral escape of gases.

An engine constructed in accordance with 10 my invention may have its cycles timed in various orders; the particular form of engine chosen herein for the illustration of my invention is designed to function in the following manner:

- 15 Each of the cylinders 10 is filled with gaseous mixture, is fired, exhausted, and scavenged in exactly the same manner as its complementary cylinders, so that a description of the functioning of one will suffice for all.
- 20 A given cylinder, upon coming into registration with the inlet-port 50, will receive through the port 18 of the rings 11 and 12 and through its open outer end a charge of explosive gaseous mixture under pressure, at 25 which time the piston of the cylinder now being described is near the limit of its inward radial movement. Upon passing out of registration with the inlet-port 50, the gaseous mixture will be compressed by the outward movement of the piston, and upon 30 reaching a nearly vertical position within the top of the casing, will have the compressed gaseous mixture within ignited by a spark-plug 73, thereby exerting an inward thrust 35 upon the piston, with the effect of imparting a clockwise impulse to the cylinders as a group, together with the cylinder coupling-ring 11, facing-ring 12, crank-case ring 14, and associated parts.
- 40 When the piston within the cylinder being described nears the limit of its inward radial movement, its port 18 will have moved into registration with the exhaust-port 48, thus permitting the burned gases to escape outward through the said port and through an 45 exhaust-pipe 74.

The continued movement of the cylinder will bring it into registration with the scavenging-air port 49, at which time, also, its 50 piston will have retired radially inward sufficiently to uncover the scavenging-air ports 51 in the cylinder walls. Immediately upon the uncovering of the ports 51, as described, air under pressure will be permitted to flow 55 into the cylinder from the air-channel 52 and outward through the port 18 and scavenging-air port 49 and carry with it any residual burned gases which may have failed to pass out through the exhaust-port 48 aforesaid.

60 The continued clockwise movement of the cylinder will move it out of registration with the scavenging-air port 49 and again register it with the intake-port 50, the piston 28, meanwhile, traveling slightly outward, so as 65 to recover the air-ports 51 in the cylinder

wall, so as to prevent the ingress of any scavenging air at this time. The cylinder is now in position to receive a fresh charge of gaseous mixture and will again pass through the cycle previously described.

By means of my invention, I am enabled to construct a simple and reliable engine with a high ratio of horse power per pound weight, since I am enabled, in a simple and reliable manner, to cause the same to function 70 as a two-cycle engine, whereby the six cylinders shown in the drawings have a power-output substantially equal to that of a twelve-cylinder four-cycle engine. Furthermore, I am enabled to dispense with valves, together 75 with the cams, levers, etc., for operating the same and to avoid many of the objections common to prior engines of this general type. Thus, when functioning through the cycle above described, centrifugal force acts to assist the expulsion of burned gases and to assist the passage of scavenging air through the cylinders.

By introducing scavenging air under pressure into the cylinders, between the exhaust 90 and intake cycles thereof, I am enabled to largely counteract the tendency of centrifugal force, which ordinarily at this time is free to throw oil outward from the crankcase and past the pistons.

I claim:

1. An internal combustion engine, comprising a stationary casing; inlet, outlet and scavenging-air ports formed in said casing; a rotary group of radially-arranged cylinders located within said casing; a piston within each of said cylinders; a scavenging-air port formed in the side wall of each cylinder near the inner end thereof and positioned so as to be uncovered by a piston therein when the same is in line with the said scavenging-air port in the casing; an air-duct connecting the said scavenging-air ports in the side wall of each cylinder with a source of air under pressure; a second port also formed in each cylinder near the outer end thereof and adapted to register with said inlet, outlet and scavenging-air ports of the said stationary casing; a stationary crank-shaft; and connecting-rods extending between each of said pistons and the said stationary crank-shaft; whereby when the said port in the outer end of each cylinder is brought into registration with the scavenging-air port in the said casing, air under pressure will be automatically admitted into the inner end of a given cylinder for positively forcing the residual gas through the scavenging-air port in the casing.

2. An internal combustion engine, comprising a stationary casing; a stationary cylinder-head ring carried by the said casing; inlet, outlet and scavenging-air ports formed in the said ring; a rotary group of radially-arranged cylinders located within the said casing and ring; a piston within each of the said

- cylinders; a scavenging-air port formed in the side wall of each cylinder near the inner end thereof and positioned so as to be uncovered by a piston therein when the same is in line with the said scavenging-air port in the casing; an air-duct connecting the said scavenging-air port in the side wall of each cylinder with a source of air under pressure; a second port also formed in each cylinder near the outer end thereof and adapted to register with the said inlet, outlet and scavenging-air ports of the said cylinder-head ring; a stationary crank-shaft; and connecting-rods extending between each of said pistons and the said stationary crank-shaft.
3. An internal combustion engine, comprising a stationary casing; inlet and outlet ports formed in the said casing; a rotary group of radially-arranged cylinders located within said casing; a coupling-ring extending between the outer ends of the said cylinders; a port formed in each of said cylinders and adapted to register with the inlet and outlet ports of the said stationary casing; an annular inwardly-opening fluid-receiving sealing-channel formed in the said casing at one side of the ports therein; sealing fluid located in the said channel; an impeller-ring carried by the said rotating group of cylinders and projecting into the said sealing-channel in the casing so as to outwardly hurl the fluid therein by centrifugal force so as to form a gas-proof seal between the said coupling-ring and the said casing.
4. An internal combustion engine, comprising a stationary casing; inlet and outlet ports formed in the said casing; a rotary group of radially-arranged cylinders located within said casing; a coupling-ring extending between the outer ends of the said cylinders; a port formed in each of said cylinders and adapted to register with the inlet and outlet ports of the said stationary casing; an annular inwardly-opening fluid-receiving sealing-channel formed in the said casing at one side of the ports therein; sealing fluid located in the said channel; an impeller-ring carried by the said rotating group of cylinders and projecting into the said sealing-channel in the casing so as to outwardly hurl the fluid therein by centrifugal force so as to form a gas-proof seal between the said coupling-ring and the said casing.

In testimony whereof, I have signed this specification.

JOHN McKLUSKY.
